UNITED STATES PATENT OFFICE

HUGO GOLDBERGER, OF NEW YORK, N. Y., ASSIGNOR TO NOVELTEX, INC., OF NEW YORK, N. Y., A CORPORATION OF NEW YORK

DESIGN FOR AN APRON

Application filed November 17, 1932. Serial No. 46,015. Term of patent 3½ years.

To all whom it may concern:

Be it known that I, HUGO GOLDBERGER, a citizen of the United States, and a resident of New York city, (borough of Manhattan), in the county of New York and State of New York, have invented the new, original, and ornamental Design for an Apron, of which the following is a specification.

Reference is had to the accompanying drawing in which—

The figure is a plan view of an apron showing my new design.

The detailed illustration shown at the left-hand side of the apron is extended on the opposite side, as indicated by the extensions beyond the dot and dash lines.

I claim:

The ornamental design for an apron substantially as shown and described.

HUGO GOLDBERGER.
